INVENTOR

ALVA MONTEL

BY

W. H. Eastwood
ATTORNEY

UNITED STATES PATENT OFFICE.

ALVA MONTEL, OF CLAYPOOL, INDIANA.

FENCE-POST.

1,250,617.

Specification of Letters Patent. Patented Dec. 18, 1917.

Application filed February 26, 1914. Serial No. 821,280.

To all whom it may concern:

Be it known that I, ALVA MONTEL, a citizen of the United States, and a resident of Claypool, county of Kosciusko, and State of Indiana, have invented a certain new and useful Fence-Post; and I do hereby declare that the following is a full, clear, and exact description thereof, reference being had to the accompanying drawings, in which

10 like letters refer to like parts.

The object of this invention is to provide a metal fence post which may be cheaply constructed and to which the wire fencing may be easily and quickly attached and which, after placed in the ground, will be firmly held therein. It consists of sheet metal bent longitudinally in an angular shape with its edges bent inwardly with a plurality of slots made in the angle in which the wire fencing may be inserted, and a rod is adapted to be inserted between the inner surface of the angle and the wire fencing. This rod is the means of easily constructing the fence and firmly holds the fencing in

25 the slots.

The bottom portion of the post has the inwardly bent edges and the sides pinched together so as to form a pocket in which dirt will settle after the post is driven into

30 the ground and holds it firmly therein so as not to be easily withdrawn.

The full nature of the invention will be understood from the accompanying drawings and the following description and

35 claim.

In the drawings, Figure 1 is an elevation of the post and fence in perspective. Fig. 2 is a front elevation of the post. Fig. 3 is a sectional elevation on the line 3—3 of Fig. 4. Fig. 4 is a top end view of the post. Fig. 5 is a cross section on the line 5—5 of Fig. 6. Fig. 6 is an enlarged view of a portion of the post, showing the details thereof. Fig. 7 is the retaining rod. Fig. 8 is a sectional view on the line 8—8 of Fig. 5.

There is shown in the drawings herein a fence post 10 formed of sheet metal and

bent longitudinally at an angle 11 and the edges 12 are turned inwardly, as shown in Fig. 5. A plurality of slots 14 are cut in the angle of the post at different intervals from the ground through which an equal number of fence wires 15 are inserted. A retaining rod 16 is then inserted between the inner surface of the angle 11 and the fence wires 15 so as to firmly hold them in said slots. At the lower end of the post, the turned in edges 12 and the base of said post are arranged together to form a pocket, as shown in Figs. 5 and 8, in order that the post may be easily driven into the ground and the dirt forming in said pocket retain it firmly in place.

Thus a fence post is made out of one piece of sheet metal which may be quickly and cheaply constructed and be quickly set up so as to retain the fence. The turning inwardly of the edges will protect animals from hurting themselves and the forming of the pockets in the lower end will materially strengthen it in the ground.

The invention claimed is:

A fence post made of metal plate bent transversely and centrally to form two castings at substantially right angles to each other and with the edges of each wing turned inward and backward substantially parallel with the wing and bent inwardly and downwardly against the body of the wing at the bottom so as to provide the post with two cup-shaped pockets at its lower end, one pocket in each wing, said inwardly bent portion being extended at an angle to form a tapering surface and the downwardly bent portion extending vertically and resting against the face of the wing whereby the post may be readily driven into the ground.

In witness whereof I have hereunto affixed my signature in the presence of the witnesses herein named.

ALVA MONTEL.
